UNITED STATES PATENT OFFICE

JOHN E. HARVEY, OF MILTON, MASSACHUSETTS.

THERMOSTATIC CIRCUIT-BREAKING APPARATUS FOR ELECTRICAL HEATERS.

1,174,006.

Specification of Letters Patent. Patented Feb. 29, 1916.

Application filed April 3, 1915. Serial No. 18,906.

To all whom it may concern:

Be it known that I, JOHN E. HARVEY, a citizen of the United States, and resident of Milton, in the county of Norfolk and

5 State of Massachusetts, have invented certain new and useful Improvements in Thermostatic Circuit-Breaking Apparatus for Electrical Heaters, of which the following is a specification.

10 This invention relates to means for automatically breaking an electric circuit through a heating unit when the heat rises above a predetermined degree, and as here shown is embodied in a sterilizing apparatus, which includes a tank; a heating unit adapted to heat the bottom of the tank; a movable circuit-closing and breaking member in circuit with the heating unit, and held in circuit-breaking position; arresting 15 means adapted to hold said member in circuit-closing position; thermostatic means connected with said arresting means in such manner that upon the overheating of the bottom of the tank, in consequence of the 20 evaporation of water therefrom, the said movable member is released and caused to break the circuit and thus discontinue the heat.

Of the accompanying drawings forming 30 a part of this specification: Figure 1 represents a longitudinal section of a sterilizing apparatus embodying my invention, the plane of said section being indicated by the line 1—1 of Fig. 2; Fig. 2 represents a top 35 plan view, the tank being removed, a part of the heating unit broken away and certain parts shown in section; Fig. 3 represents a section on line 3—3 of Fig. 2; Fig. 4 represents a section on line 4—4 of Fig. 3, looking upwardly; Fig. 5 represents a fragmentary elevation of a portion of the tank and the bracket and detent holder; Fig. 6 represents a section on line 6—6 of Fig. 3; Fig. 7 represents a perspective view of the 40 bracket; Fig. 8 represents a perspective view of the inner section of the detent lever; Fig. 9 is a view similar to Fig. 2, showing a different embodiment of the invention; Fig. 10 represents a section on line 10—10 of 45 Fig. 9; Fig. 11 represents a section on line 11—11 of Fig. 9; Fig. 12 represents a fragmentary perspective view showing details 50 hereinafter referred to.

Referring first to Figs. 1 to 8 inclusive,— 55 12 represents a casing which may be of sheet metal and of rectangular form, and is sup-

ported by a horizontal base 13 having a flange 13^a which surrounds the lower edge portion of the casing, the base being provided with legs 13^b. As here shown, the 60 horizontal portion of the base has an opening 13^c covered by a relatively thin sheet metal bottom plate 13^d, the other portions of the base being preferably formed as a single casting. The casing is provided with downwardly projecting bolts 12^a offset inwardly 65 from its inner surface and passing through holes in the base, said bolts being provided with nuts 12^b. The said bolts and nuts detachably secure the casing to the base and 70 permit the heating unit and other parts hereinafter described, supported by the base, to be assembled before the casing, the tank, and the hereinafter described thermostat and detent lever supported thereby are located on the base.

14 represents a tank attached at its upper edge to the upper edge of the casing 12, the sides of the tank being preferably inclined, as shown by Figs. 1 and 3, to form an air 80 space. The bottom of the tank is elevated above the base to form a space in which the hereinafter described heating unit, the thermostat and the circuit-making and breaking devices controlled by the thermostat are located.

The heating unit as here shown is a resistance wire 16, disposed in beds or loops in a body 17 (Figs. 1 and 2) of suitable insulating and heat-conducting material, 90 such as mica or porcelain, in contact with the bottom of the tank, and supported by a shallow pan 18. A layer 19 of asbestos is preferably interposed between the body 17 and the bottom of the pan to prevent the 95 downward radiation of heat. The pan is supported and spaced from the base by bolts 20 attached to the bottom of the pan and passing through orifices in the base, the bolts being separable from the base and provided with nuts 21 bearing on opposite surfaces of the base, and detachably securing the bolts thereto.

The thermostat is composed of a brass tube 22 soldered or brazed along its entire 105 length to the bottom of the tank, and a steel rod 23, which extends loosely through the tube 22. One end of the rod 23 is provided with an adjustable head or abutment bearing on one end of the tube 22, and preferably composed of two nuts 24 engaged with a threaded portion of the rod, one nut 110

- locking the other at the desired adjustment. One end of the tube 22 is soldered or brazed in a recess 27^a, formed for its reception in a fixed bracket 27 (Fig. 7) which supports 5 the inner section or member 28 of a swinging detent, forming a part of the circuit-breaking and closing means hereinafter described, controlled by the thermostat. The bracket 27 includes rivet-engaging ears 27^b bearing on the bottom of the tank; a perforated ear 27^c, and an arm 27^d having a perforated ear 27^e in alinement with the ear 27^c, the recess 27^a being in an enlargement of the arm, and the bracket being preferably cast in one piece. The detent-lever section 28 includes a bar 28^a formed to enter the space between the bracket ears 27^c, 27^e, longitudinally perforated at 28^b to receive a fulcrum pin 29, which connects it with said 15 ears; an arm 28^c on one end of said bar slotted to receive an eye on one end of the thermostat rod 23, and perforated to receive a pintle 29^a, which connects the arm with said rod, and an elongated arm 28^d, which extends at right angles with the arm 28^c.

30 represents the outer member or section of the detent lever, this section being adapted to engage a finger on the movable switch member hereinafter described. The section 30 is pivoted at 31 to the arm 28^c of the inner section, and has two arms preferably of unequal length. The shorter arm is pressed by a spring 32 against an adjustable stop screw 33 on the arm 28^c, said spring being coiled about a fixed stud 32^a on the base and having two arms, one bearing on a fixed stud 34 on the base, and the other on a stud 35 in the shorter arm of the lever section 30. The two lever sections 25 and 30 constitute a bell-crank lever, one arm of which is formed by the arm 28^c, and the other by the arm 28^d, and the outer section 30. The object of the sectional construction of the lever is to permit the lateral adjustment of its outer end by the screw 33, for a purpose hereinafter described.

The outer end portion of the detent-lever section 30 is formed to detachably engage 50 a finger or projection on the movable member of a circuit-closing and breaking switch composed of a fixed member and a movable member, said members, when in contact with each other, closing the circuit through the heating unit, and breaking said circuit when separated. In this embodiment of the invention, I have shown a circuit-closing and breaking device of the knife switch type, one member of the switch including two spaced-apart contact springs or strips, 36, 36^a, while the other member includes a contact bridge 37 formed to enter and bridge the space between said springs, as shown by Fig. 1, thus closing an electric circuit, which 55 includes the springs, the bridge and the

heating unit. When the bridge 37 is withdrawn from between the contact springs, as shown by Fig. 4, the circuit is broken.

The contact bridge is attached to an oscillatory lever or carrier, which is fulcrumed 70 on a stud 39 fixed to the base, and, as here shown, is composed of two members 38 and 38^a, the latter being insulated from the former (38), and screwed or riveted to the contact bridge. 75

The contact bridge 37 is on one end of the carrier, and the opposite end of the carrier is provided with a finger 38^c formed to engage a notch 38^a in the detent-lever section 30, as shown by Fig. 2. 80

40 represents a spring which is coiled on the fulcrum stud 39 and has two arms, one bearing on a fixed stop stud 41, and the other on a stud 38^d on the carrier member 38. Said spring normally holds the carrier in the position shown by Fig. 4 with contact bridge separated from the contact springs, and the circuit broken. The engagement of the finger 38^c with the detent-lever section 30 holds the contact bridge 37 90 in contact with the contact springs, and prevents the spring 40 from acting.

44 represents a push piece movable in a guide 45 in the base, and connected by a link 46 with the carrier member 38, said push 95 piece being manually movable to move the finger 38^c into engagement with the detent-lever notch 30^a, as shown by Fig. 2.

The electric circuit includes a wire 47 electrically connected by a conducting strip 100 47^a (Fig. 2) with the contact spring 36, and with one end of the resistance wire of the heating unit 16, a wire 48 connecting the opposite end of the resistance wire with a plug 49, and a wire 50 connecting the companion 105 plug 51 with a conducting strip 50^a electrically connected with the other contact spring 36^a.

When the plugs 49, 51, are connected with a source of electrical energy, and the 110 contact bridge 37 is in the position shown by Figs. 1 and 2, the heating unit acts to heat the contents of the tank 14.

When the heat of the bottom of the tank exceeds a predetermined degree, as a result, for example, of the evaporation of water from the tank, the resulting expansion of the tube 22 of the thermostat exceeds that of the rod 23, and the tube is caused by its elongation to act on the rod shoulder 115 120 formed by the nuts 24 and exert a pull on the rod. This pull swings the detent lever in the direction of arrow α (Figs. 2, 4 and 8), and disengages its outer section 30 from the contact-bridge carrier, whereupon the 125 spring 40 acts to move the bridge 37 to its circuit-breaking position, and cause the cooling of the tank bottom. After the cooling has sufficiently continued, the contact bridge may be again locked in its circuit- 130

closing position by an inward movement of the push piece, the latter having been forced outwardly, when the circuit was broken.

The detent-lever section 30 has an oblique face 30^b on which the finger 38^c bears, when moving to engage the notch 30^a. The entire detent lever and the thermostat rod 23 are adapted to be displaced by the passage of the finger over the oblique face, the nuts 24 separating slightly from the end of the tube 22, after which the spring 32 presses the notched end of the detent lever into engagement with the finger.

The length of the expanding movement of the tube 22 depends mainly on the adjustment of the top screw 33 on the detent-lever section 28, said screw being adjustable to move the notch 30^a either to the right or to the left and permit the breaking of the circuit, when the tank bottom is heated to any predetermined degree within certain limits. The spring 32 holds the section 30 against the screw 33 at all adjustments. The longer arm of the detent lever is enabled, by the described construction, to be flexed or bent to vary the position of its notched outer end. The nuts 24 on the rod 23 may also be used in effecting the described adjustment.

In a sterilizing apparatus comprising a water tank, the adjustment of the screw 33 should be such that the circuit will be broken, when the heat of the tank bottom exceeds 212° F., the boiling point of water. Injurious overheating of the tank and its contents after the water boils away may be, therefore, automatically prevented.

While I have specified a knife switch as the preferred form of circuit-closing and breaking device, I do not limit myself thereto and may use any suitable device including contact members, which are separable by a spring acting on one of said members. The spring 40 should be sufficiently strong to give the movable contact member a circuit-breaking movement, which is quick enough to obviate or minimize injury to the contact members by sparking when they are being separated.

In the above described embodiment of the invention the detent lever 30, which acts to release the movable switch member carrier 38, is moved by direct mechanical connections between it and the thermostat member 22, when the latter is expanded by the heat of the tank.

To guard against failure to break the circuit when the temperature rises to the predetermined point, it is necessary to so adjust the notch 30^a that a relatively slight movement of the arm 30 will release the finger 38^c. This renders the engagement of the notch and finger somewhat sensitive, so that they are liable to be prematurely or accidentally disengaged by shocks or jars, such as those caused by moving the apparatus

from one location to another. To obviate this objection I have devised the means shown by Figs. 9, 10, 11 and 12, whereby the thermostat formed by the members 22 and 23, instead of acting entirely through mechanical connections to break the circuit, acts to close a circuit through a secondary heating unit resistance, which in turn acts on a secondary thermostat, the latter in turn acting to release the movable member of the spring-impelled circuit-closing and breaking device. In this embodiment of the invention the thermostat composed of the members 22 and 23 may be called the primary thermostat. The member 23 is pivoted at 55 to the shorter arm of a lever 56 which is fulcrumed at 57 to ears 58 on a bracket 59 (Fig. 12) having ears 60 which are screwed or riveted to the bottom of the tank.

The lever 56 has at the end of its longer arm a collar 56^a of insulating material bearing on the upright arm of a bell-crank lever 61, which is fulcrumed at 61^a to a fixed bracket 62^a attached to and insulated from the base. The horizontal arm of the lever 61 projects under a lever 62 and is normally out of contact therewith, as shown by Fig. 11. The lever 62 is fulcrumed at 63 to a fixed bracket 64 insulated from the base, and is pressed downward by a spring 65 against an adjustable bearing screw 66 engaged with the base, the lever being provided with an insulated stud 67 bearing on said screw.

The levers 61 and 62 and brackets 62^a, 64, constitute parts of an electric circuit which includes a secondary heating unit 68, said current being normally broken by the separation of the levers 61 and 62 shown by Fig. 11. The lever 56 constitutes a means for closing said circuit by moving the lever 61 into contact with the lever 62 when the primary thermostat is expanded by heat.

The secondary heating unit is embedded in an elongated tube 70 of insulating material which contains the secondary thermostat hereinafter described, said tube being supported by brackets 71, 72, attached to the base. One end of said unit is connected by a wire 73 with the bracket 64 and the other end by a wire 74 with a contact spring, or strip 75 which is the upper member of a pair of spaced-apart contact springs, the lower member of which is designated by the numeral 76, said springs being insulated from each other. The spring 76 is connected by wire 77 with the terminal plug 49, which is connected by wire 78 with one end of the tank heating unit 16', which is supported and arranged like the unit 16 previously described.

The opposite end of the unit 16' is connected at 79 with a contact spring or strip 80 which is the upper member of a pair of

spaced-apart contact springs, the lower member of which is designated by the reference numeral 81, said springs being insulated from each other. The spring 81 is 5 connected by wire 82 with the terminal plug 51, and this plug in turn is connected with the bracket 62^a by wire 83.

The secondary thermostat is composed 10 of a brass tube 22' inclosed in the tubular holder of the secondary heating unit and attached at one end to the bracket 72, and a steel rod 23' extending through the tube and having nuts 24' bearing on the free end of the tube.

15 85 represents an oscillatory carrier fulcrumed at 86 on the base, and engaged by a spring 40', which has the same function as the spring 40, in that it causes the breaking of the circuit through the primary or 20 tank heating unit, and the added function of causing the breaking of the circuit through the secondary heating unit. In performing these functions the spring 40' swings the carrier in the direction indicated 25 by arrows z, z, from the position shown by Fig. 9, and thus removes two contact bridges 88 and 89 carried by it at opposite sides of its fulcrum from positions between and in contact with the contact springs 75, 76, and 30 80, 81, said bridges being insulated from the carrier 85.

When the apparatus is set for operation, the spring 40' is prevented from performing 35 its functions by a detent lever 90 fulcrumed at 91. The shorter arm of said lever is pivoted at 92 to the rod 23' of the secondary thermostat, and the longer arm has a notch 93 engaging the reduced end of the carrier 40 85. It will now be seen that when the apparatus is in the condition shown by Figs. 9, 10 and 11, the primary heating circuit is closed through the terminal plug 49, wire 78, unit 16', spring 80, bridge 89, spring 81, wire 82, and terminal plug 51, and the 45 circuit through the secondary unit 68 is broken, because the lever 61 is normally held out of contact with the lever 62, as shown by Fig. 11, by a spring 94. (Fig. 9).

When the primary thermostat is expanded by the heat of the tank bottom, it 50 swings the lever 56 in the direction indicated by arrow y (Fig. 9) against the pressure of a spring 95 which normally holds said lever in the position shown by Fig. 9. 55 This movement of the lever 56 moves the bell-crank lever 61, and causes it to make contact with the lever 62. The secondary heating unit circuit is now closed through the terminal plug 51, wire 83, bracket 62^a, lever 61, lever 62, bracket 64, wire 73, unit 68, wire 74, spring 75, bridge 88, spring 76, wire 77 and terminal plug 49. The primary heating unit circuit remains closed 60 until the secondary thermostat is sufficiently expanded by the heat developed by 65

the secondary unit to swing the detent 90 to the left from the position shown by Fig. 9. When this occurs the carrier 85 is released and the spring 40' acts to swing the carrier and break the circuit through the 70 two heating units.

A spring 90^a (Fig. 9) may be provided to restore the detent 90 to its carrier-engaging position when this is permitted by the cooling of the secondary thermostat. 75

The last described construction avoids any premature or accidental circuit breaking which may occur when the apparatus is organized as first described, because at 210° the switch member carrier 38 must be 80 held in the notch 30^a while the current is heating the element 16. At the same time the detent lever 30 must release the carrier 85 at a few degrees above 212°. Now according to the second construction, the 85 secondary thermostat may be at a temperature of approximately 200° when the secondary heating element is not in operation. When the secondary circuit is closed, however, the secondary thermostat will be raised 90 to from 400° to 500° in a few seconds, so that the carrier is released by a relatively ample movement of the lever 90 due to a rise in temperature of from 300° to 400°, instead of by a relatively slight movement 95 of the detent lever 30 due to a rise in temperature of a few degrees.

The bearing screw 66 constitutes the equivalent of the screw 33 as an adjusting means for varying the extent of movement 100 of the primary thermostat required for the performance of its function.

Each of the above described embodiments of the invention includes a movable carrier having circuit-breaking and closing means 105 and normally held by means such as the spring 40 or the spring 40' in circuit-breaking position, arresting means such as the detent 30, or the detent 90, normally adapted to hold said carrier in circuit-closing position, and thermostatic means, which may include the tank-heated thermostat only, and direct mechanical connections between said thermostat and the arresting means, or may include the tank-heated primary thermostat and the secondary thermostat, the latter constituting a member of the connections between the primary thermostat and the arresting means, and retarding the circuit-breaking action of 110 the primary thermostat. 115

Having described my invention, I claim:

1. In combination, an electrical heating unit; a body heated thereby; a movable carrier having circuit-breaking and closing 125 means in circuit with said unit, said carrier being normally held in circuit-breaking position; arresting means normally adapted to hold said carrier in circuit-closing position; and thermostatic means operated by 130

an increase of temperature of said body for making said arresting means inoperative.

2. In combination, an electrical heating unit; a body heated thereby; a movable carrier having circuit-breaking and closing means in circuit with said unit, a spring normally holding said carrier in circuit-breaking position; arresting means normally adapted to hold said carrier in circuit-closing position; and thermostatic means operated by an increase of temperature of said body for making said arresting means inoperative.

3. In combination, an electrical heating unit; a body heated thereby; a movable carrier having circuit-breaking and closing means in circuit with said unit, said carrier being normally held in circuit-breaking position; arresting means normally adapted to hold said carrier in circuit-closing position; thermostatic means operated by an increase of temperature of said body for making said arresting means inoperative; and adjusting means for regulating the action of the thermostatic means.

4. In combination, a primary heating circuit including an electrical heating unit; a body heated thereby; a secondary heating circuit including a thermostat-heating unit; a movable carrier having circuit-breaking and closing members in circuit with said units, said carrier being normally held in circuit-breaking position; arresting means normally adapted to hold said carrier in circuit-closing position; a primary thermostat arranged to be heated by said body; secondary circuit-closing means actuated by said primary thermostat; a secondary thermostat arranged to be heated by the secondary heating unit; and means operated by the secondary thermostat for making said arresting means inoperative.

5. In combination, an electrical heating unit; a body heated thereby; a movable carrier having circuit-closing and breaking means in circuit with said unit, said carrier being normally held in circuit-breaking position; arresting means normally adapted to hold said carrier in circuit-closing position; a thermostat arranged to be heated by said body; and means intermediate the thermostat and the arresting means for rendering the latter inoperative when the thermostat is expanded.

55 6. In combination, an electrical heating unit; a body heated thereby; a movable carrier having circuit-closing and breaking means in circuit with said unit, said carrier being normally held in circuit-breaking position; arresting means normally adapted to hold said carrier in circuit-closing position; a thermostat composed of an elongated metal tube and a metal rod passing loosely through the tube and having a shoulder at one end bearing on one end of

the tube; and means intermediate the opposite end of the rod and the arresting means, for rendering the latter inoperative when the thermostat is expanded.

7. In combination, an electrical heating unit; a body heated thereby; a movable carrier having circuit-closing and breaking means in circuit with said unit; said carrier being normally held in circuit-breaking position; a detent normally adapted to hold said carrier in circuit-closing position; a thermostat arranged to be heated by said body; and means intermediate the thermostat and detent for moving the latter to a carrier-releasing position when the thermostat is expanded.

8. In combination, an electrical heating unit; a body heated thereby; a movable carrier having circuit-closing and breaking means in circuit with said unit, said carrier being normally held in circuit-breaking position; a detent normally adapted to hold said carrier in circuit-closing position; a thermostat arranged to be heated by said body; and means intermediate the thermostat and detent for moving the latter to a carrier-releasing position when the thermostat is expanded, said means having provisions for retarding the carrier-releasing movement of the detent.

9. In combination, an electrical heating unit; a body heated thereby; a movable carrier having circuit-closing and breaking means in circuit with said unit, said carrier being normally held in circuit-breaking position; a detent normally adapted to hold said carrier in circuit-closing position; a thermostat arranged to be heated by said body; and means intermediate the thermostat and detent for moving the latter to a carrier-releasing position when the thermostat is expanded, said means including a secondary heating unit, a secondary thermostat arranged to be heated thereby, and devices for closing the circuit through the secondary heating unit when the thermostat is heated by the body is expanded.

10. In combination, a sterilizing tank; a casing surrounding the tank; a base supporting the casing and tank, said base and casing forming a space below the bottom of the tank; and heat-controlling means located in said space and comprising an electrical heating unit arranged to heat the tank, a movable carrier having circuit-breaking and closing means in circuit with said unit, said carrier being normally held in circuit-breaking position, arresting means normally adapted to hold said carrier in circuit-closing position, and thermostatic means operated by an increase of temperature of said tank for making said arresting means inoperative.

11. In combination, an electrical heating unit; a body heated thereby; a movable car-

95

100

110

120

125

130

rier having circuit-closing and breaking means in circuit with said unit, said carrier being normally held in circuit-breaking position; a detent normally adapted to hold 5 said carrier in circuit-closing position; a thermostat arranged to be heated by said body; and means intermediate the thermostat and detent for moving the latter to a carrier-releasing position when the thermostat is expanded, said means including a secondary heating unit, a secondary thermostat arranged to be heated thereby; and devices 10 for closing the circuit through the secondary heating unit when the thermostat heated by the body is expanded, said means including 15 a primary thermostat heated by the tank, a secondary heating unit energized by the action of the primary thermostat, and a secondary thermostat heated by the secondary heating unit.

12. In combination, a sterilizing tank; a

casing surrounding the tank; a base supporting the casing and tank, said base and casing forming a space below the bottom of the tank; a heat-controlling means located 25 in said space and comprising an electrical heating unit arranged to heat the tank, a movable carrier having circuit-breaking and closing means in circuit with said unit, said carrier being normally held in circuit-breaking position, a detent normally adapted to arrest said carrier in circuit-closing position, a thermostat arranged to be heated by the tank, means intermediate the thermostat and detent for moving the latter to a 30 carrier-releasing position when the thermostat is expanded, and a push piece manually movable in the base and adapted to cause the re-engagement of the carrier and detent. 35

In testimony whereof I have affixed my 40 signature.

JOHN E. HARVEY.
